(57) **CLAIM**

The ornamental design for a weather shield for skylight window, as shown and described.

DESCRIPTION

FIG. 1 is a perspective view taken from the top, front and left side of a weather shield for skylight window showing a first embodiment of the design;

FIG. 2 is a front elevation of the weather shield for skylight window of FIG. 1;

The rear, left side, and right side elevations of the weather shield for skylight window of FIG. 1 are each identical to the front elevation of FIG. 2;

FIG. 3 is a bottom plan view of the weather shield for skylight window of FIG. 1;

FIG. 4 is a top plan view of the weather shield for skylight window of FIG. 1;

FIG. 5 is a perspective view taken from the top, front and left side of a weather shield for skylight window showing a second embodiment of the design;

FIG. 6 is a left side elevation of the weather shield for skylight window of FIG. 5;

The right side elevation of the second embodiment of the design is a mirror image of the left side elevation;

FIG. 7 is a front elevation, on a slightly larger scale than FIG. 6, of the weather shield for skylight window of FIG. 5;

The rear elevation of the second embodiment of the design is a mirror image of the front elevation;

FIG. 8 is a bottom plan view of the weather shield for skylight window of FIG. 5; and,

FIG. 9 is a top plan view of the weather shield for skylight window of FIG. 5.
